UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

HARNESS MECHANISM FOR LOOMS.

Application filed June 3, 1924. Serial No. 717,527.

To all whom it may concern:

Be it known that I, CLARE H. DRAPER, a citizen of the United States, residing at Hopedale, in the county of Worcester and 5 State of Massachusetts, have invented certain new and useful Improvements in Harness Mechanism for Looms; and I do hereby declare the following to be a full, clear, and exact description of the invention, such as 10 will enable others skilled in the art to which it appertains to make and use the same.

The present invention relates to an improvement in harness mechanism for looms, and more particularly that part of the harness mechanism for looms by which the harness is supported from the loom frame. 15

In the operation of looms when a warp thread breaks the warp must be pieced. It is a convenience in piecing the warp to drop 20 all the harnesses to one level.

The object of the present invention is to produce a simple and efficient mechanism for this purpose. To this end the present invention consists in the harness mechanism 25 hereinafter described and particularly defined in the claims.

In the accompanying drawings illustrating the preferred form of the invention, Fig. 1 is a front elevation of a portion of 30 the loom illustrating the harness supporting mechanism, showing the harnesses in lowered position; Fig. 2 is a similar elevation of the mechanism showing the parts in the position they assume when the harnesses are 35 in raised position; Fig. 3 is a detail of a sheave bracket hereinafter referred to; Fig. 4 is a side elevation of the harness mechanism; and Fig. 5 is a detail hereinafter referred to.

40 The illustrated embodiment of the invention is described as follows: The arch 1 of the loom frame supports a bracket 2 which extends upwardly from one end of the arch. In the upper end of this bracket the main 45 stud 3 is secured. This main stud carries the main lever 4 which is pivotally mounted on the stud, being held thereon by means of a cotter pin 5. The upper arm 6 of the main lever carries a sheave stud 7 secured 50 to the arm 6. On this stud are rotatably mounted the sheaves or strap pulleys 8 and 9. The pulleys are integral and held on the stud 7 by a collar 10. The other end 11 of the main lever 4 carries a stud 12. On

this stud is mounted the quadrant lever 13. 55 The upper portion of this lever, as viewed in Fig. 2, is a quadrant 14, and the lower end of this lever is a resetting handle 15. The quadrant 14 is provided with a notch 16 for a purpose presently to be stated. Also 60 mounted on the stud 12 is the secondary lever 17. The upper end 18 of this lever is provided with a release latch 19 pivoted at 20 on the secondary lever and normally pressed to the right, as viewed in Fig. 5, 65 by a spring 21. This release lever 19 is adapted to engage the notch 16 in the segment above referred to. The lower end 22 of the secondary lever 17 carries a stud 23 which constitutes the support for the sheaves 70 or belt pulleys 24 and 25. They are integral and rotatably mounted on the stud and secured thereon by means of the collar 26.

The harness straps are attached to the sheaves or strap pulleys in the usual manner. Thus, the strap 31 extends around the pulley 8, and is secured thereto by the screw 41, the strap 32 extends around the pulley 9 and is secured thereto by the screw 42, the strap 33 extends around the quadrant 14 75 and is secured thereto by the screw 43, the strap 34 extends around the pulley 24 and is secured thereto by the screw 44, and the strap 35 extends around the pulley 25 and is secured thereto by the screw 45. The strap 80 35 supports the foremost harness H by means of the two connections 55 and 65. The other straps similarly support the other harnesses. Each strap 31, 32, 33, 34 and 35 supports one harness frame. When the 85 front harness frame is raised the strap 35 is pulled upon and another strap is released to allow its harness to descend. When the harness frame attached to the strap 33 is raised, both the straps 34 and 35, or straps 90 31 and 32, are lowered to permit their harness frames to descend, and so on, in the usual manner. The strap brackets 70 are mounted on the arch of the loom, and each carries a stud 71, and each such stud bears 100 five sheaves 72, being held on the stud by the collar 73.

The operation of this harness mechanism for lowering the harnesses to a uniform level for convenience in piecing the warp is as 105 follows: Under ordinary circumstances all of the harness straps are tight, and if in such condition the release lever 19 be pulled

upon, it will withdraw it from the notch 16. Then the tension on the harness straps will tend to pull the top sheaves 8 and 9, and the bottom sheaves 24 and 25, toward each other, thereby swinging the main lever to the right, and the secondary lever to the left, as shown in Fig. 2, and the tension on the strap 33 will tend to swing the quadrant lever to the right, as viewed in such figure, but the balance of the pressures will result in the parts assuming the position illustrated in Fig. 1. That is to say, the resetting handle of the quadrant lever and the release latch will be raised, and the quadrant will be swung to the right, as shown in Fig. 1, and all of the belts will be released, and piecing may be accomplished. When the piecing is finished the operative will take hold of the resetting handle 15 and 20 the release latch 19, press downward upon them, thereby tightening all of the belts, and will finally move the quadrant in left hand rotation to the position shown in Fig. 2, and the release latch to its right hand or 25 lowered position, whereupon the release latch will catch in its notch in the quadrant, and the parts will be held in the position to which they have been brought.

It will be observed that the quadrant lever 30 13 and the secondary lever 17 being secured together during normal operation of the loom are in effect one lever, and that the latch and quadrant connection between them constitutes the means by which it may be 35 broken for harness levelling. We have, therefore, virtually two levers, the one being the main lever 6, and the other consisting of the connected quadrant and secondary levers 13 and 17. It will be apparent also 40 that we have means by which one of the two levers may be broken for levelling the harnesses.

It will be observed that the mechanism is extremely simple and inexpensive, certain in 45 operation, and durable.

Having thus described the invention, what is claimed is:

1. A harness mechanism for looms having, in combination, a support, a main lever 50 pivotally mounted on the support, having one arm carrying sheaves or harness strap

pulleys, and a second arm, another lever pivotally mounted on the second arm of the main lever consisting of two parts, one provided with a notch and the other provided 55 with a latch, the two parts of the latter lever being adapted to be locked together by the latch and notch, and provided each with sheaves or harness strap pulleys.

2. A harness mechanism for looms having, in combination, a support, a main lever pivotally mounted on the support, one arm of which carries a plurality of harness strap attaching means, another lever pivotally mounted on the arm of the main lever and 60 carrying a plurality of harness strap attaching means, one of said levers having means by which it may be broken for leveling the harnesses.

3. A harness mechanism for looms having, in combination, a support, a main lever pivotally mounted on the support, one arm carrying harness strap attaching means, and having also a second arm, a quadrant lever pivoted on the second arm of the main lever, 75 a secondary lever pivoted at the same point on the main lever as the quadrant lever and provided with harness strap attaching means, said secondary lever carrying a release latch, and said quadrant lever being 80 provided with a segmental guide for the latch and having a notch to receive said release latch and hold the harness straps under tension.

4. A harness mechanism for looms having, in combination, a support, a main lever pivotally mounted on the support, said main lever having two arms, one of which carries a plurality of attaching means, a quadrant lever pivoted on the other arm of the main lever, a secondary lever pivoted to the same point on the main lever as the quadrant lever, said quadrant lever and secondary lever being provided with a plurality of harness strap attaching means, said secondary lever 90 carrying a release latch, and said quadrant lever being provided with a notch to receive said release latch to hold the harness straps under tension.

In testimony whereof I have signed my 100 name to this specification.

CLARE H. DRAPER.
